UNITED STATES PATENT OFFICE

ALFRED FALLOT, DECEASED, LATE OF PLAUN IN VOGTL., GERMANY, BY HARRY PRIESTER, EXECUTOR, OF BERLIN, GERMANY

MEANS FOR RAISING, CHANGING, AND DRIVING THE PAPER WEB ROLLS IN PRINTING MACHINES AND MORE PARTICULARLY IN ROTARY PRINTING MACHINES

Application filed January 8, 1926, Serial No. 80,130, and in Germany January 20, 1925.

This invention relates to an improvement in or modification of the paper roll raising, changing and feeding device described and claimed in the present inventor's patent application Ser. No. 68006 and the object of the present invention is to simplify the construction and operation of the device so as to render it more effective and reliable.

The invention is illustrated in the accompanying drawings, in which:

Figure 1 is a side elevation of the improved device.

Figure 2 is an end elevation showing the spent and the new paper roll between the two uprights.

Figure 3 is a section in a vertical plane of one of the traversing bearers.

Figure 4 is a section on the line A—B of Fig. 3.

Figure 5 is a section on the line C—D of Fig. 3.

Figure 6 is a plan of a traversing bearer with the top cover removed.

In carrying the invention into effect, the paper roll is mounted on a shaft *b*, which may be arranged in two parts as is well known or may pass through the paper roll *a* and be wedged or keyed thereto in any well known manner. The shaft *b* together with the roll *a* are adapted to be traversed up or down the vertical standards or uprights *e* at each side of the machine. In addition to the vertically traversing bearers *c*, there are the transfer bearers *d*, which are movable horizontally, out of the path of the ascending paper roll spindle and after the spindle has been traversed past the transfer bearer, these bearers again project forward and take under the paper roll spindle. The paper roll spindle is now lowered by lowering the traverse bearers *c*, whereby the spindle *b* is picked up by the transfer bearers and the traverse bearers are traversed to their lowest positions when they are in position and in condition to receive a fresh roll. The operation described is similar to that described in the main patent application mentioned above.

The paper roll is driven or braked as found necessary by contacting with an end-

less band *f* which is itself driven at the speed of the printing machine. The lower drum *f*¹ of this endless band is the driven member and the upper drum *f*² is arranged in any convenient manner to act as a tensioning member. By moving the traverse bearers *c* upward the paper roll may be caused to contact with the belt with any desired pressure or for a greater or lesser angle so as to alter the frictional contact by means of which the drive is transmitted.

The traverse bearers are constructed of box form and act as gear cases for enclosing and supporting the gearing by means of which the paper roll is automatically raised to retain it with uniform pressure against the band *f* as the diameter of the roll decreases in unwinding. The spindle *b* of the paper roll is provided at each projecting end part with broad teeth *b*¹ which enable endwise adjustment of the paper roll whilst still keeping the teeth in gear with a gear wheel *n* mounted on the same shaft as a gear wheel *o* of smaller diameter which meshes with a pinion *q*, Figure 5 on a shaft *q*¹ on which there is fixed or keyed a worm screw *p*. The worm screw *p* engages with a worm wheel *p*¹ mounted on the same shaft as a bevel wheel *r* meshing with another bevel wheel *i*. The bevel wheel *i* is internally threaded and engages on a vertical threaded spindle *e*¹ mounted as a traverse shaft in front of the traverse way of the upright *e*. The arrangement described is duplicated at each side of the machine as will be understood from Figure 2.

The drive through the worm screw *p* and the worm wheel *p*¹ is non-reversible, that is to say the drive can be transmitted from the worm to the worm wheel but not from the worm wheel to the worm. The direction in which the worm *p* rotates the nut *i* is that required to cause the nut to rise on the threaded traverse spindle *e*¹. At the upper end of the nut *i* there is a ball thrust bearing on which a sleeve *c*² cast on the traverse bearer box rests. The sleeve *c*² is a loose sliding fit on the exterior of the traverse screw spindle *e*, which passes through the said sleeve. The front of the upright *e* is

recessed out to admit the free passage of the sleeve c^2 and has side ledges e^2 which are embraced by corresponding side cheeks on the traverse bearer as can be seen in Figure 5. The traverse bearer is thus efficiently guided in a steady manner in its travel up or down the guide on the upright e .

The traverse screw spindle e^1 is supported at its bottom end in a suitable footstep bearing and at its upper end in a bushing fixed to the side of the machine and carrying a housing for a worm wheel g which engages with a worm on a cross shaft k adapted to be driven by a motor h . The electric motor h is reversible and may be controlled by hand from a switch board m or automatically by switch levers l and l^2 connected by a rod l' and adapted to be operated by strikers l^3, l^3 on the top and bottom of the left hand traverse bearers c in Figure 2.

The operation of the device described above is as follows. The paper roll a is trundled along the floor until the spindle b is over the journal of the traverse bearer c , as in the main patent application, and the motor h is then switched on from the switch board m to start the upward traverse of the traverse bearers c . Both traverse bearers c rise simultaneously and pick up the spindle b , the teeth b^1 and the teeth of the wheel n being suitably chamfered or eased off to ensure that the spindle does not ride on the top of the teeth but drops properly into engagement with the teeth of the wheel n . The hoisting movement of the traverse bearers is continued until the paper roll a presses with an adequate pressure on the band f whereupon the roll a is caused to rotate. The paper web is threaded through the machine and printing continues. In winding off the paper the roll a and spindle b rotate and thereby the drive is transmitted from the teeth b^1 to the nut i and the traverse bearers are thus slowly raised to maintain the pressure of the roll on the band f after the motor h has been switched off. When the roll has been unwound to the extent that the traverse bearers have brought the spindle b opposite the inclined face of the transfer bearers d , which as can be seen in Figure 2 engage the spindle b nearer the central plane of the web than the bearer c , these transfer bearers are pushed from left to right in Figure 1, until the spindle b has passed over them, whereupon they snap back and engage under the spindle b of the nearly spent paper roll. The switch l is now struck by the top striker l^3 whereby the motor h is automatically started and the bearers c lowered. The motor drives the traverse spindle e^1 which is caused to rotate and as the nut i is locked by its drive as described above, the nut i is traversed along the traverse spindle e^1 and the bearers in virtue

of their weight follow the downward motion of the nut i . The printing machine continues to draw off web from the nearly spent roll in the transfer bearers d during the time the traverse bearers c are being lowered to receive the fresh roll. The fresh roll is picked up by the traverse bearers after these have been lowered till the striker l^3 on the bottom of the traverse bearer c has stopped the motor by operating the switch lever l^2 . The operations described above are then repeated and the fresh web is joined by a gummed strip to the spent web which is then severed and the spindle b cast off from the transfer bearer d in the manner described in the main patent application. The apparatus described may be adapted as described in the main patent application for use with a machine printing a plurality of webs simultaneously or for a machine in which the traverse of the bearers C is in a horizontal instead of a vertical direction.

It will be observed that in the present invention, the traverse screw spindle is employed or rotated to effect the operations required at changing the web, whilst the nut i is rotated for the slow gradual raising of the traverse bearers c for the purpose of maintaining the required degree of driving contact with the paper roll and the band f as the diameter of the paper roll a decreases.

The sidewise adjustment of the paper web is also effected by means located in the box shaped traverse bearers c or the bearer c at the left hand side in Fig. 2. The spindle b rests on ball bearings b^2 housed as shown in Figure 4, in the box shaped traverse bearers c . The spindle b has also at the left hand end in Figs. 2 and 4 a circumferential groove b^3 in which a shifting fork t engages. The fork t is slidably mounted in a boss u^1 in a rack u which is guided in the traverse bearer c to slide parallel to the axis of the spindle b . The fork t is under the action of a spring located in the boss u^1 so that if the groove b^3 is not opposite the fork t when the spindle b is placed in the bearer c the fork can slip back out of the way. The rack u engages with a worm screw v^1 on a shaft v mounted in the bearer case and operable by a handwheel as shown in Fig. 6. If the fork t has not nested in the groove b^3 when the traverse bearer c picked up the spindle b the hand wheel may operate the screw v^1 and rack u till the fork does snap into the groove b^3 , after which the hand wheel may be operated till the web of the freshly inserted roll is in line with the edge of the web of the roll in the machine. During the operation of changing the web or roll the printing machine is preferably run at slow speed.

It will be understood that the invention is

not limited to the details of construction herein described.

What is claimed is:

1. A paper roll changing and driving device for use in printing machines such as rotary printing machines, comprising in combination, a paper roll spindle, traverse bearers for said paper roll spindle, threaded sleeves in said traverse bearers, traverse spindles in engagement with said threaded sleeves, means for rotating said sleeves on the traverse spindles, other means independent thereof and serving for rotating said spindles and transfer bearers adapted to automatically take up the paper roll spindle when being brought into contact with the same.

2. A paper roll changing and driving device for use in printing machines such as rotary printing machines, comprising in combination, a paper roll spindle, traverse bearers for said paper roll spindle, traverse spindles in engagement with said traverse bearers, frictional endless driving means for 25 rotating the said paper roll spindle with a paper roll on the same, during the upward movement of the said paper roll spindle, means operated by the paper roll spindle for raising the said paper roll spindle and keeping the paper roll thereon in contact with the said frictional driving means and other means for adjusting the pressure of the frictional driving means against said paper roll.

3. A paper roll changing and driving device for use in printing machines such as rotary printing machines, comprising in combination, a paper roll spindle, traverse bearers for said paper roll spindle, traverse spindles in engagement with said traverse bearers, means for frictionally engaging a paper roll on said paper roll spindle, rotating the same and feeding the paper web to the printing machine, other means driven by the paper roll spindle for raising the same and keeping the paper roll thereon in contact with the frictional rotating means, transfer bearings adapted to automatically take up the paper roll spindle at the end of its upward movement, a motor for rotating the traverse spindles and switching devices arranged at the uppermost and at the lowermost position of the paper web spindle and being adapted to be operated automatically by the same, in order to start and stop the said motor.

4. A paper roll changing and driving device for use in printing machines such as rotary printing machines, comprising in combination, a paper roll spindle, traverse bearers for said paper roll spindle, traverse spindles in engagement with said bearers, means for raising said traverse bearers substantially vertically, other means for rotating a paper roll on said paper roll spindle and feeding the web of the roll to the print-

ing machine, transfer bearings adapted to automatically take up the paper roll spindle at the end of its upward movement, a motor for rotating the traverse spindles, automatically operated devices for starting and stopping such motor at predestined positions of the paper roll spindle and an apparatus for adjusting axially the position of said paper roll spindle in its bearers.

In testimony whereof I have signed my name to this specification.

HARRY PRIESTER,
*Executor for the Estate of Alfred Fallot,
Deceased.*
